(57) **CLAIM**

The ornamental design for a magnetic storage device, as shown and described.

DESCRIPTION

FIG. 1 is a perspective view of the magnetic storage device. FIG. 2 is a front elevational view of the magnetic storage device.

FIG. 3 is a top plan view of the magnetic storage device.

FIG. 4. Is a rear elevational view of the magnetic storage device.

FIG. 5 is a bottom plan view of the magnetic storage device.

FIG. 6 is a left side elevational view of the magnetic storage device; and,

FIG. 7 is a right side elevational view of the magnetic storage device.

1 Claim, 4 Drawing Sheets

FIG. 1

FIG. 3

FIG. 2

FIG. 4**FIG. 5**

FIG. 6

FIG. 7
